(57) **CLAIM**

The ornamental design for a pressed palm leaf dish, as shown and described.

DESCRIPTION

FIG. 1 is a perspective view of the pressed palm leaf dish, according to a first embodiment;

FIG. 2 is a top plan view of the first embodiment of the invention;

FIG. 3 is a front elevation view of the first embodiment of the invention, the rear elevation view being a mirror image;

FIG. 4 is a bottom plan view of the first embodiment of the invention;

FIG. 5 is a right side view of the first embodiment of the invention, the left side view being a mirror image;

FIG. 6 is a perspective view of the first embodiment of the invention in use with a cover thereon;

FIG. 7 is a perspective view of the pressed palm leaf dish, according to a second embodiment;

FIG. 8 is a top plan view of the second embodiment of the invention;

FIG. 9 is a front elevation view of the second embodiment of the invention, the rear elevation view being a mirror image;

FIG. 10 is a bottom plan view of the second embodiment of the invention;

FIG. 11 is a right side view of the second embodiment of the invention, the left side view being a mirror image; and,

FIG. 12 is a perspective view of the second embodiment of the invention in use with a cover thereon.

The broken lines in the drawings represent unclaimed environmental subject matter and form no part of the claim.

1 Claim, 4 Drawing Sheets
